UNITED STATES PATENT OFFICE.

EDWARD E. CLEMENT, OF WASHINGTON, DISTRICT OF COLUMBIA.

DESIGN FOR AN AUTOMATIC TELEPHONE-SWITCH FRAME.

No. 39,144.

Specification for Design.

Patented Feb. 18, 1908.

Application filed December 23, 1905. Serial No. 293,142. Term of patent 14 years.

To all whom it may concern:

Be it known that I, EDWARD E. CLEMENT, a citizen of the United States, residing at Washington, in the District of Columbia, have invented a new, original, and ornamental Design for Automatic Telephone-Switch Frames, of which the following is a specification, reference being had to the accompanying drawing.

Figures 1 and 2 are a side elevation and a vertical edge view respectively.

I claim:

The ornamental design for an automatic telephone switch frame, as shown.

EDWARD E. CLEMENT.
